UNITED STATES PATENT OFFICE.

ALBERT SCHWARZ, OF NEW YORK, N. Y., ASSIGNOR OF ONE-HALF TO ISIDORE M. LASHINSKY, OF NEW YORK, N. Y.

PARACHUTE.

Application filed October 12, 1923. Serial No. 668,068.

Among the principal objects which the present invention has in view are: to control the falling speed of a parachute and person supported thereby; to augment the supporting power of a parachute; to accelerate the spread of the parachute; to provide mechanical manually released means for spreading the parachute; and to adapt the parachute for control by the passenger.

Drawings.

Figure 1 is a vertical section of a parachute, constructed and arranged in accordance with the present invention, the preferred form thereof being shown as in operation.

Figure 2 is a side elevation showing a fragment of the same in folded condition.

Figure 3 is a detailed view on enlarged scale showing the preferred means for controlling the spread of the parachute.

Figure 4 is a section thereof, the section being taken on the line 4-4 in Fig. 3.

Figure 5 is a detailed view showing a modified means for controlling the spread of the parachute.

Figure 6 is a cross section thereof, the section being taken on the line 6-6 in Fig. 5.

Description.

As seen in the drawings the preferred construction of the parachute provides an umbrella-like cover 11 which is spread on radially disposed ribs 12, the inner ends whereof are pivotally mounted on a crown ring 13, similar in construction to that of the usual umbrella.

The crown ring 13 is preferably fixed on a staff 14 on which slide the telescopically arranged tubes 15 and 16. The tube 16 has an extension 17 at the lower end of which is an anchorage ring 18 to which each of the various cables 19 is secured.

The outer ends of the cables 19 are made fast to the outer ends of the ribs 12. The inner ends of the ribs 12 as above stated are pivotally attached to the crown ring 13. Intermediate the ends of the ribs 12, each is secured to one of the brace rods 20, the inner ends whereof are each pivotally connected to the tube 15. The brace rods 21 which are pivotally secured to the tube 16 are also pivotally connected to the rods 20

to be acted upon by the collapsing of the 55 ribs 12.

It will be seen in Fig. 5 of the drawings that when the tube 15 is drawn down or retracted, the ribs 12 press upon and force downward the inner ends of the rods 21 60 and the tube 16 connected therewith. This operation has the effect of compressing the spiral spring 22 which rests between and within the tubes 15 and 16. When permitted the spring 22 expands and forces the tubes 65 15 and 16 apart, as shown in Figures 1 and 3 of the drawings, with the result that the rods 20 and 21 are spread outward carrying therewith the portions of the ribs 12 to which they are operatively connected.

From the foregoing, it will be seen that when released, the spring 22 mechanically operates to spread the ribs 12 of the parachute. It is equally obvious that when the tubes are drawn downward the ribs 12 are 70 contracted. For this purpose a windlass 23 is furnished in the preferred form of the construction, a handle 24 serving to operate the same whenever the detent 25 engages the teeth of a ratchet 26 formed on the hub 75 of the windlass.

The windlass 23 is normally mounted loosely on the shaft 27 with which the handle 24 is permanently engaged. Wound on the windlass 23 is a light but strong cable 80 28, the free end of which is connected with the ring 18. The operation of the windlass 23 is manual, the operator standing upon a platform 29, which as shown best in Fig. 3 of the drawings is attached permanently to 85 the staff 14.

In Fig. 1 of the drawings, there is disclosed a plurality of parachutes, one fitting within the other. The ribs 30 of the larger parachute are retained in permanent relation to the ribs 12 by the connecting cords 31. By this means, whenever the lower ends, 90 of the inner parachute are contracted, the same result is obtained in the ribs of the outer parachute.

Both parachutes are provided at the apex thereof with suitable openings or spillways for the air, as in parachutes of usual construction.

With a parachute constructed and arranged as above disclosed, one seeking to 100 make a descent with the parachutes in the folded condition as shown in Fig. 2 of the

- drawings, steps off into space with one or both feet on the platform 29. The detent 25 is immediately disengaged from the windlass 23, which allows the spring 22 to expand with the result that the inner ends of the rods 20 and 21 are forced apart to the position shown in Fig. 3, which operation forces the ribs 12 outward to the fully opened position of the parachute. The horizontal stress exerted on the ribs 30 of the outer parachute quickly adjust these to the out-spread position, the maximum carrying capacity of the parachute being thus early established.
- If now the operator desires to quicken his descent, he grasps the handle 24 and by means of the grip 32, places the detent 25 in engagement with the teeth of the ratchet 26 and begins to wind the windlass 23. The winding of the windlass 23 lowers the tubes 15 and 16 and the inner ends of the rods 20 and 21, thereby contracting the spread of the lower parachute. The ends of the ribs 12 are drawn down in correspondence with the lowered position of the ring 18. This is also true of the ribs 30 of the larger parachute, the cords 31 accomplishing this purpose.

From the foregoing, it will be seen that the aviator may at all times control the speed of descent of the parachute upon which he is a passenger.

In Figures 5 and 6, a modified form of the invention is shown, the modification consisting in the provision of a rack toothed section on the staff 14. A gear wheel 34 is engaged therewith to raise and lower the same whenever rotated by means of the manipulated handle 35. The handle 35 is engaged with the wheel 34 only when the grip 36 is forced inward by the hand of the operator when grasping the handle 37. This construction is best shown in Fig. 6 of the drawings.

When it is desired to maintain in any established position the parachutes, the lock bars 38 and 39 are inserted in the paths of the teeth of the ratchet 23 or in the path of the orifice 40 provided in the wheel 34.

It is obvious, that while I have described a parachute having small and large carrying members with means for contracting and expanding the lower edges or spreads thereof, that the construction may be variously altered without departing from the spirit of the invention.

It is also obvious that means associated with the tubes 15 and 16 operatively connected with the material forming the openings or spillways at the apex of the parachutes may be employed for increasing or diminishing the said openings or spillways, with the effect that the descent of the parachute would be altered in accordance with the operation. This arrangement could be readily effected by making fast or permanent the lines or cords 19 and 31 on the staff 14, while others of a similar character could connect the edges of the said spillways and the ring 18 to operate so that with the adjustment of the said ring 18 the spillway could be increased or diminished.

Claim:

In a parachute, a staff, a ribbed parachute assembly attached thereto, a pair of nesting sleeves slidable over said staff and in pivotal connection with ribs of said parachute assembly, a spring on said staff compressible between said sleeves for spreading said parachute on compression release through movement of said sleeves, a slidable rack bar in said staff, connection between said bar and parachute assembly, and manually operable rack bar operating means on said staff for moving said bar to contract said parachute against action of said spring.

ALBERT SCHWARZ.
